UNITED STATES PATENT OFFICE.

PETER DE MATTIA AND BARTHOLD DE MATTIA, OF GARFIELD, NEW JERSEY.

COLLAPSIBLE CORE FOR VEHICLE-TIRES.

1,135,774.

Specification of Letters Patent. Patented Apr. 13, 1915.

Application filed January 15, 1914. Serial No. 812,342.

To all whom it may concern:

Be it known that we, PETER DE MATTIA and BARTHOLD DE MATTIA, citizens of the United States, and residents of Garfield, in the county of Bergen and State of New Jersey, have invented a new and Improved Collapsible Core for Vehicle-Tires, of which the following is a full, clear, and exact description.

10 Our invention relates to collapsible cores for use in manufacture of tire shoes.

The object thereof is to provide a simple, strong and inexpensive device which can be easily and quickly assembled or demounted, 15 which core on its inner periphery presents a single annular member, thereby increasing the resistance of the core to the spreading action taking place at the inner periphery of the core when the same is used for vul- 20 canizing purposes.

We attain the above object by providing a single core formed of core segments and adapted to be received by a single annular member and secured thereto by suitable 25 means adapted to draw said segments to said annular member and toward the axis of said annular member.

The invention consists of the construction and combination of parts to be more fully 30 described hereinafter and fully set forth in the claims.

Reference is to be had to the accompanying drawings forming a part of this specification, in which like characters indicate 35 corresponding parts in both views and in which:

Figure 1 is an elevation of a core embodying our invention; and Fig. 2 is a section on line 2—2, Fig. 1.

40 Referring to the drawings, 3, 4, 5 and 6 represent the four segments or sections forming the circular core. The contacting ends of the parts 4 5 and 5 6 are directed radially, while the contacting ends of the parts 3 4 45 and 3 6 converge outwardly toward the outer periphery of the core, so that the segment 3 can be easily removed toward the center of the core, thereby permitting collapsing the core, as is customary for such 50 cores.

Each of the segments on the inner periphery is provided with a flanged portion 7 on the margin of which a lateral projection 8 is formed, said flanged portion 7 of 55 each section, with the lateral projection 8, forming together a continuous annular

flange and a continuous lateral projection on one side of said core. The inner lateral surface of each of the segments is beveled, as shown at 9 in Fig. 2, with a portion 9' of said inner periphery remaining cylindrical. The purpose of this will appear hereinafter.

The segments or sections of the core are bound together by means of a single annular member 10 provided with an annular recess 11 on one side of the outer periphery thereof. The recess 11 has a cylindrical portion 12 parallel to the axis of said annular member adapted to be engaged by the cylindrical portion 9' of the projection 8. The portion 13 of the recess normal to the axis of said member and, therefore, at right angles to the portion 12 of said recess is adapted to be engaged by the sides 14 of the flanges 7 of said segments. The said recess has also a beveled or angularly disposed bottom 15 connecting the parts 9 and 12 of the recess 11 and substantially parallel to the bevel 9 of the segments. Each of the segments is secured to the annular member by means of bolts 16, which bolts are carried by the annular member 10, with the heads 17 of the bolts positioned in recesses 18 provided on the inner periphery of said annular member. The threaded ends of the bolts project into the recess 11 substantially at right angles to the beveled bottom 15 of said recess, each end engaging a threaded opening 19 provided in the projection 8, 90 said threaded opening being substantially perpendicular to the beveled portion 9 of said sections. The threaded openings are preferably provided adjacent the ends of the sections, as shown in Fig. 1, so that each 95 section is secured by means of two bolts to the single ring or annular member 10. The action of each of said bolts is to draw its section into the recess 11 and toward the axis of said annular member. The drawing 100 action of said bolts on said sections therefore is toward the annular member and angularly toward the axis of said member.

The diameter of the cylindrical portion 12 of the recess 11 is such as to bring the ends 105 of said segments of the core together at the same time as their cylindrical portion 9' comes in contact with the said portion 12 of the annular member. Simultaneously with the engagement of the cylindrical surface 9' and 12, the surface 13 of the recess 11 comes in contact with the sides 14 of the segments, thus

the inner parts of the segments are wedged in the recess 11 of the annular member by the bolts 16. The cylindrical part 20 of the annular member, lying to one side of the flange 7, forms on said flange a lateral projection similar to the projection 8 on the opposite side of said flange. The purpose of this is to form on each side of the section a support for the casing; and this not forming a part of this invention is not illustrated.

The V-shaped groove 21 is provided on the inner periphery of the annular member for engagement by the spreader such annular member will offer a greater resistance, being a unit in itself, that is, a single member, than in the ordinary cores at present in use in which the spreader engages the segments of the core directly.

Having thus described our invention, we claim as new and desire to secure by Letters Patent:

1. In a collapsible core for vehicle tires, a circular core member formed of segments, each of said segments having on the inner periphery thereof a lateral projection, said projections of said segments forming together an annular lateral projection on said circular core member, each of said segments having on the inner periphery of said projections a beveled surface; a single annular member having an annular recess on the outer periphery thereof at one side of said member, said recess having a beveled bottom therein adapted to co-act with the beveled surface of said segments; and locking means carried by said annular member for securing said segments to said annular member, said locking means being disposed at substantially right angles to the beveled bottom of said recess of said annular member whereby they draw said segments into said recess angularly and toward the axis of said annular member.

2. In a collapsible core for vehicle tires, a circular core member formed of segments, each of said segments having a lateral pro-

jection at the inner periphery thereof, said segments with the projections thereon forming together an annular flange portion with the lateral projection on said circular core member, each of said segments at the lateral projection having at its inner periphery a beveled surface; a single annular member having an annular recess at one of its outer edges, said recess having a beveled bottom and the sides of said recess being adapted to engage the inner periphery of the lateral projection of each of said segments and a portion of a side of each of said flanges of said segments; bolts carried by said annular member, the threaded end of said bolts projecting into said recess of said annular member substantially at right angles to the beveled bottom of said recess, said segments having threaded openings in the lateral projection adapted to be engaged by the threaded ends of said bolts, whereby said segments are wedged in said recess of said annular member by the drawing action of said bolts on said segments, said drawing action being angular and toward the axis of the annular member, substantially as and for the purpose set forth.

3. In a collapsible core for tires, a circular core formed of arcuated segments, each segment having a bevel surface at the inner periphery, an annular member forming a support for said segments, and bolts mounted to rotate in said annular member and engaging said segments at the bevel side and at right angles to said side, said annular member having means adapted to guide each of the segments normally to the axis of the core and parallel thereto.

In testimony whereof we have signed our names to this specification in the presence of two subscribing witnesses.

PETER DE MATTIA.
BARTHOLD DE MATTIA.
